UNITED STATES PATENT OFFICE.

CLARENCE W. THORNILEY, OF ELECTRA, TEXAS.

WELL-DRILLING APPARATUS.

1,092,309.

Specification of Letters Patent. Patented Apr. 7, 1914.

Application filed December 11, 1912. Serial No. 736,156.

To all whom it may concern:

Be it known that I, CLARENCE W. THORNILEY, citizen of the United States, residing at Electra, in the county of Wichita and 5 State of Texas, have invented certain new and useful Improvements in Well-Drilling Apparatus, of which the following is a specification.

My invention relates to well-drilling machinery, and has for its object the simplification of apparatus for the stated purpose so that the parts may be more compactly arranged than heretofore and the operating mechanism more easily set up in position 15 where a well is to be drilled.

The invention seeks to provide a well-drilling apparatus in which the several lines will be under the complete control of the operator and will be arranged in such compact form that they may be inclosed so that 20 injury to the operator will not be apt to occur.

The invention is illustrated in the accompanying drawings and consists in certain 25 novel features which will be hereinafter first fully described and then more particularly pointed out in the appended claims.

In the drawings: Figure 1 is a perspective view of my improved well-drilling apparatus showing the same arranged for 30 spudding; Fig. 2 is a side elevation showing the same arranged for drilling; Fig. 3 is a plan view; Fig. 4 is a detail perspective view of a portion of the gearing.

The mud sills 1 consist of heavy beams disposed in parallel relation adjacent the 35 location of the well as usual, and my improved machinery is to be mounted upon a frame 2 which is adapted to be slid endwise over the sills and consists of lower beams or 40 sills 3, posts 4 erected on said sills, upper beams 5 secured upon said posts, and cross bars connecting the several sills or beams.

The upper beams 5 are of different lengths, 45 as shown most clearly in Figs. 1 and 3, thereby providing space at the front end of the frame to accommodate the bull wheel and the casing line wheel, the bull wheel being extended laterally beyond the main 50 frame and supported by a standard or post 6 secured to and rising from a beam or sill 7 adapted to rest upon the mud sills parallel with the side of the main frame and connected therewith by a beam 8 extending over 55 the lower sills 3 of the main frame and held thereto by clips or brackets 9. Upon the

longitudinal faces of the lower sills 3, I secure laterally projecting plates or ribs 10 which are adapted to slide under keepers or overhanging brackets 11 on the mud sills 60 and thereby hold the frame in position upon the sills and prevent it rising. The standard 6 and the supplemental frame will be connected with the main frame by suitable braces as may be necessary.

The samson post 12 is secured upon the cross bar at the front extremity of the frame and is braced by a bar 13 secured thereto near its upper end and extending downwardly and rearwardly therefrom to 70 the upper side beam 5 of the frame to which it is secured. The samson post is inclined slightly rearwardly from the front end of the frame so that the frame may be used in connection with the ordinary derrick, and, 75 when so used, may have its front end placed between the posts of the derrick and connected thereto in any convenient manner so as to bring the bull wheel and the other operating mechanism close to the derrick and 80 thereby relieve the strain upon the different lines and permit the several operations to be efficiently performed with shorter lines than has heretofore been possible. The walking beam 14 is fulcrumed upon the upper end of the samson post in the usual manner, and a connecting rod 15 is pivoted at its upper end to the rear end of the walking beam and is adapted to have its lower end pivoted to the crank 16 on the end of 85 the main shaft 17. The main driving shaft 17 is rotated through suitable connections with any convenient form of engine or motor, and upon the said shaft, between the sides of the supporting frame, is fixed a 90 large driving wheel 18 which also serves as a fly-wheel. At one side of this drive wheel 18 is provided a beveled pinion or friction wheel 19 which is in engagement with a bevel pinion 20 carried by the rear end of a 95 shaft 21 which is journaled in a short standard or other support 22 on the frame, and in a bracket 23 secured upon the side beam of the frame. A beveled pinion 24 is splined upon the shaft 21 and is adapted to be 100 moved axially thereon by a fork 25 formed on the end of a lever 26 which is fulcrumed upon the main frame adjacent the said pinion, as shown and as will be readily understood. This pinion 24 is so disposed as to 105 mesh with a beveled wheel 27 on one end of the bull wheel 28 which carries the drill line,

so that, by shifting the pinion into mesh with the beveled spur wheel 27, the bull wheel may be rotated to wind the drill line thereon when it is desired to remove the tools from the well. The drill line will be engaged by the walking beam in the usual manner so as to be actuated thereby when drilling and the drill line 29 will be kept in the proper taut condition upon the bull wheel by a brake band 30 secured at one end to the main frame and passing over the end of the bull wheel, as clearly shown. The free end of this brake band is constructed with a hook 31 which is engaged by a pin 32 on the end of a brake lever 33 which is fulcrumed in the main frame, so that, by swinging the lever downwardly and forwardly, the brake band will be drawn closely around the edge of the end member of the bull wheel and thereby prevent rotation of the same.

In starting the well, the connecting bar 15 is disengaged from the crank 16 and a link or connecting rod 34 is engaged on the said crank, the rear end of said link or connecting rod being pivoted to the lower end of a spudding lever 35 which is pivoted between its ends at the rear end of the main frame. To the upper end of this spudding lever is secured a jerk line 36, the front end of which is loosely engaged around the drill line, as clearly shown. The rotation of the driving shaft will then oscillate the spudding lever and, through the jerk line, will actuate the drill line, so as to alternately raise and lower the same in the usual manner.

The casing line 37 is wound upon a casing wheel 38 which is suitably mounted upon the lower sills or beams of the main frame immediately adjacent the front end thereof and has its shaft extended laterally beyond one side of the frame and equipped with a grooved pulley 39, as shown. A cable or chain, indicated in dotted lines in Fig. 1, is trained around the pulley 39 and a double pulley or idler 39' mounted on the frame below the driving shaft and a second chain or cable is trained around the idler and a pulley 40 on the driving shaft, so that the casing wheel may be rotated when necessary, the speed of rotation being controlled by a brake band 41 passing around one end of the wheel and operated by means of a brake lever 42 which is fulcrumed upon the front end of the frame, as shown in Fig. 1.

Upon the upper portion of the main frame, at the rear end thereof, is journaled a shaft 43 upon which is a friction wheel 44 constituting one end of the sand line wheel and adapted to be moved into operative engagement with the driving wheel 18 by a lever 45 which is fulcrumed upon the main frame at the rear end thereof below the shaft 43 and carries one end of said shaft. The

lever is controlled by a rod 46 and the speed of the said friction wheel 44 may be controlled by a brake shoe 47 secured upon the frame in rear of said wheel, the manipulation of the rod 46 causing the wheel to bear upon the brake shoe or against the driving wheel, as will be readily understood.

At the front end of the main frame, I secure, preferably by a hinge 49, which may be on either the front or the rear side of the cross bar, the mast 50 which extends upwardly and outwardly from the frame and which, when the apparatus is in use, will be braced by suitable guy-wires 51. At the upper end of the mast 50 is fitted a large pulley 52 over which the drill line 29 runs, and below the said pulley are similar pulleys 53 over which the casing line 37 and the sand line 54, respectively, run. It will be readily noted that the mast may be swung backwardly over the frame so that the apparatus may be readily moved from place to place and, when in use, the mast will transmit pressure downwardly to the main frame so as to hold the same in its position.

At the rear end of the frame is provided an eye or bracket 55 to which may be attached any convenient form of anchoring device 56.

In starting the operation of the apparatus, the spudding lever 35 is connected to the main driving shaft and the drill line, as shown in Fig. 1 and indicated in dotted lines in Fig. 2, and the main drive shaft then rotated, as will be readily understood. When the drilling has progressed to a depth of one hundred or one hundred and twenty-five (100 or 125) feet the spudding lever is disconnected and the walking beam is then connected up to the main drive shaft, as indicated by dotted lines in Fig. 1 and by full lines in Fig. 2. The drilling then proceeds in the usual manner, the pinion 24 being thrown out of mesh with the spur wheel 27 so that the shaft 21 will run free and the descent of the tools being regulated by the pressure exerted through the brake band 30. As the drilling proceeds and it is necessary to lower the casing into the well, the casing line wheel is permitted to rotate by releasing the pressure exerted thereon by the brake band 41 so that the said line may descend into the well. Should it be necessary to withdraw the casing or the drilling operation should be completed so that the tools should be withdrawn, the pinion 24 is thrown into mesh with the wheel 27 and the casing line wheel is permitted to rotate under the influence of the pulleys 39 and 40 and the chain or cable trained around the same, it being understood that any convenient device may be provided to hold the chain or cable loose upon the pulleys when the casing is being lowered but to tighten the same on the pulleys when the casing is to be

130

raised. When it is desired to operate the sand line or bailer, the lever 45 is vibrated so as to throw the friction wheel 44 into direct contact with the drive wheel 18 so that 5 the sand wheel will be rotated.

It will be readily seen from the foregoing description, taken in connection with the accompanying drawings, that I have provided a well drilling mechanism in which 10 the operating parts are very compactly arranged so that they may be inclosed by a suitable casing, if necessary, and the operator thereby protected against injury. When 15 one point to another point, the supplemental frame consisting of the standards 6, the sill 7, and the beam 8 may be shifted laterally from its engagement with the main frame and the main frame then merely slid out of 20 engagement with the keepers on the mud sills so that the machinery then may be readily moved through narrow openings or over narrow paths without difficulty or inconvenience.

25 It will be understood, of course, that either friction or toothed gearing may be used as preferred. In supplying the machine to purchasers, I contemplate supplying the wheels 19 and 20 in both forms and 30 the wheel 19 may have its operating periphery partly smooth and partly toothed to be engaged by toothed or smooth pinions interchangeably fitted on the shaft 21.

What I claim is:—

35 1. In a well drilling apparatus, the combination of a main frame comprising lower sills, posts rising therefrom and beams secured upon said posts, the beam at one side terminating short of the front ends of the 40 sills, a bull wheel mounted upon the frame in advance of said shorter beam, a supplemental frame slidable laterally into and out of engagement with the main frame and supporting one end of said bull wheel, and 45 means for operating the bull wheel.

2. In a well drilling apparatus, the combination of a main frame, a supplemental frame disposed laterally of the main frame and having a member extending transversely through the main frame, a clip on the main frame fitting over said member, a bull wheel supported by said supplemental frame and the main frame, and means on the main frame for operating the bull wheel.

3. In a well-drilling apparatus, the combination of a frame, a casing wheel mounted on the base of the frame at the front end of the same, a bull wheel mounted on the frame adjacent the casing wheel and above and in rear of the same, a driving wheel mounted 55 on the top of the frame in rear of the bull wheel, gearing at opposite sides of the frame connecting the driving wheel with the bull wheel and the casing wheel respectively, and a sand wheel mounted on the frame in rear 60 of the driving wheel and adapted to directly engage the same.

4. In a well drilling apparatus, the combination of a supporting frame, a driving shaft thereon, a beveled wheel rigid with 70 said shaft, a bull wheel mounted upon the frame in advance of the driving shaft, a beveled wheel rigid with one end of the bull wheel, an obliquely disposed transmission shaft mounted upon the side of the supporting frame, a pinion at the rear end of said shaft engaging the beveled wheel on the driving shaft, a beveled pinion splined upon said shaft and adapted to mesh with the bevel wheel on the bull wheel, and means for 80 shifting said pinion axially along the transmission shaft.

5. The combination of a frame, a driving shaft mounted transversely thereon, a bevel wheel rigid with said shaft, a bull wheel 85 mounted upon the frame in advance of said shaft, a transmission shaft mounted obliquely upon the main frame between the bull wheel and the driving shaft, a bevel pinion on the rear end of said shaft meshing with the 90 bevel wheel on the driving shaft, a bracket secured upon and rising from the main frame and supporting the front end of the transmission shaft, a bevel wheel rigid with one end of the bull wheel, a bevel pinion 95 slidably mounted on the transmission shaft and adapted to engage said bevel wheel, a standard secured upon the side of the main frame adjacent said bracket, and a horizontally disposed forked lever mounted in the 100 upper end of said standard and having its inner end engaging said bevel pinion.

In testimony whereof I affix my signature in presence of two witnesses.
